BEVELED INTERENGAGING IMPELLERS
SUPERCHARGER OR BLOWER

James W. F. Holl, Los Angeles, Calif.

Application October 9, 1945, Serial No. 621,333

4 Claims. (Cl. 230—142)

1

This invention relates to a supercharger or blower whereby gases are forced under pressure in large volume out of the blower.

An object of my invention is to provide a supercharger or blower of the disc and blade type, and in which the blades and the disc rotate on oblique axes; the disc being so mounted that it will seal against a side wall of the housing between the intake and outlet ports.

Another object of my invention is to provide a novel supercharger or blower, the housing of which is formed in two similar parts; said parts being bolted together on approximately the center line of the apparatus.

Another object of my invention is to provide a novel supercharger or blower of the character stated in which the two obliquely mounted shafts are journalled in adjustable bearings so that the rotating disc and blades can be held within close tolerances, relative to the surfaces with which they cooperate.

Still another object is to provide a novel supercharger or blower of the character stated, which can be used as a two-stage apparatus, if desired.

A feature of my invention resides in the smooth and contoured path for the flow of air, or other gases, moving through the blower.

Other objects, advantages and features of invention may appear from the accompanying drawing, the subjoined detailed description and the appended claims.

Figure 1 is a vertical sectional view of my supercharger or blower.

Figure 2 is a side elevation of the disc and blades in assembled position.

Figure 3 is a side elevation of the blade assembly, the upper portion of which being shown in section.

Figure 4 is an end view of the blade assembly.

Figure 5 is a side elevation of the housing, the upper part being broken away to show interior structure.

Figure 6 is a fragmentary sectional view taken on line 6—6 of Figure 5.

Figure 7 is a view similar to Figure 5, but with the lower part of the housing being broken away to show interior structure.

Figure 8 is a side elevation of the disc, this view showing the outside face thereof.

Figure 9 is an end view of the disc.

Figure 10 is a side elevation of the disc showing the inside face.

Referring more particularly to the drawing, my invention includes a housing 1, this housing being formed as a segment of a sphere and con-

2

sisting of two similar halves. These two halves 2 and 3 are flanged and bolted together as shown at 4. A drive shaft 5 extends into the housing and is journalled in a bearing or bearings 6; this mounting is preferably adjustable longitudinally of the bearing 6, in a manner usual for roller or ball bearings so that the interior rotating parts can be carefully adjusted and with very small tolerances between the contacting surfaces.

A drive shaft 7 is mounted oblique to the shaft 5 and is journalled in the bearing 8, which again is preferably adjustable in the usual manner and similar to the bearing 6 for the purpose of accurately mounting the parts within the housing.

15 The bearings 6 and 8 are preferably of the anti-friction type, this being the type usually employed in adjustable bearings.

A universal joint 9 couples the shaft 5 to the shaft 7 so that both of these shafts are simultaneously rotated. A disc 10 is formed with a central hub 11; this hub being substantially semi-spherical. The hub is suitably mounted on the shaft 7, that is, it is fixedly attached thereto so that the shaft, the hub, and the disc will rotate together.

20 The disc and the hub may be formed as one integral part, although this is not absolutely necessary.

25 A pair of blades 12—12 extend from a hub 13, which is spherical in shape and is adapted to fit closely within the hub 11 and with close tolerances. The hub 13 is suitably mounted on the shaft 5 so that the shaft, hub and blades rotate together.

30 The disc 10 is provided with two diametrically opposite slots 14 and 15, into which the blades 12—12 extend. The hub 11 is provided with egg- or elliptical-shaped openings 16 and 17, which extend into the slots 14 and 15, respectively. The purpose of these openings is to receive the lower part of the blades 12, and this lower blade face 18 will engage the wall of one of these openings, and will follow this elliptical- or egg-shaped path, as the disc and blades rotate.

35 It will be evident that during the rotation of the disc and blades, the relative position of the disc and blades will vary, and this variation in movement is the reason for the egg- or elliptical-shaped cutouts 16 and 17. Since the blade follows the wall of the cutout 16 or 17, it will also act as a seal at this point. The slots 14 and 15 are so formed that the blades 12—12, fitting therein, will be sealed off by the face of the slots, that is the face of the slot might be chamfered as shown in Figure 9, due to the oblique mounting

of the disc 10 within the housing. It will be evident that the outer and inner faces of the disc will closely follow a flat face of the housing indicated at 19. This contacting point of the disc lies between the inlet 20 and the exhaust 21, thus sealing the inlet from the exhaust. This arrangement is best shown in Figures 1 and 6. The exhaust and inlet combination is duplicated on the lower half of the housing, and on the opposite side as shown in Figure 1.

The second exhaust 22, being shown in this figure, adjacent inlet 23 is also provided. In Figure 6 the direction of rotation of the disc and blades is shown by the arrow.

If it is desired to use the supercharger or blower as a two-stage device, the exhaust from the bottom can be extended to the inlet at the top. Obviously any combination of upper and lower portage can be used. While I have mentioned the use of air or other gases, and for this purpose have stressed the fact that the adjacent and moving surfaces must be closely fit, it is possible to use my device with liquids, and in this instance there can be a substantially metal to metal contact between the various adjacent surfaces.

Having described my invention, I claim:

1. In a supercharger or blower, a rotatable radially bladed element, said element including a spherical hub, a rotatable slotted disc including a semi-spherical hub, the hub of the bladed element fitting within the hub of the disc, the hub of the disc having a curved wall cutout extending from the slots in said disc, an edge of the blade following the curved wall of the cutout as the disc and blades rotate, a casing, said casing having inlet and discharge ports therein arranged in the side wall thereof, said bladed element and disc being adapted to rotate on oblique axes in the casing.

2. In a supercharger or blower, a rotatable radially bladed element, said element including a spherical hub, a rotatable slotted disc including a semi-spherical hub, the hub of the bladed element fitting within the hub of the disc, the hub of the disc having a curved wall cutout extending from the slots in said disc, an edge of the blade following the curved wall of the cutout as the disc and blades rotate, a casing, said casing having inlet and discharge ports therein arranged in the side wall thereof, said bladed element and disc being adapted to rotate on oblique axes in the casing, said disc sealing with the side wall of the casing between the inlet and discharge ports.

3. In a supercharger or blower, a rotatable radially bladed element, said element including a

spherical hub, a rotatable slotted disc including a semi-spherical hub, the hub of the bladed element fitting within the hub of the disc, the hub of the disc having a curved wall cutout extending from the slots in said disc, an edge of the blade following the curved wall of the cutout as the disc and blades rotate, a casing, said casing having inlet and discharge ports therein arranged in the side wall thereof, said bladed element and disc being adapted to rotate on oblique axes in the casing, said disc sealing with the side wall of the casing between the inlet and discharge ports, the inlet and discharge ports being arranged in the side of the casing and on opposite sides thereof, there being an inlet and discharge port adjacent the upper and lower parts of the casing.

4. A supercharger or blower comprising a rotatable radially bladed element, a shaft on which the bladed element is mounted, an adjustable bearing in which said shaft is journalled, a rotatable slotted disc adapted to receive the blades of said bladed element within its slots, a second shaft on which said disc is mounted, an adjustable bearing in which the second shaft is journalled, said shafts being obliquely positioned, a universal joint connecting said shafts, a housing having a spherical-like chamber within which the bladed element and the disc are adapted to rotate on oblique axes, intake and outlet ports in said casing, a spherical hub on the bladed element, a semi-spherical hub on the slotted disc, the hub of the bladed element fitting within the hub of the disc, the hub of the disc having a curved wall cutout extending from the slots in said disc, an edge of the blade following the curved wall of the cutout as the disc and blades rotate.
